UNITED STATES PATENT OFFICE

JOSEPH F. BOINEY, OF TONAWANDA, NEW YORK

METHOD AND APPARATUS FOR DRY CLEANING

Application filed October 12, 1937. Serial No. 225,747.

This invention relates to a method and apparatus for treating material or articles, containing soluble or volatile matter which it is desired to remove therefrom.

Heretofore in the washing or cleaning treatment of certain articles it has been customary to submerge the articles in the treating liquid or washing liquid and agitate the articles so as to subject the same to the whirling action of the liquid and to bring the articles into forceful contact with the liquid so that the treatment or washing will be more or less complete. As this treating process continues the liquid becomes more or less contaminated and it is therefore impossible to completely and thoroughly treat or wash the articles unless the first liquid is drained off and a fresh supply obtained, which latter is not always convenient and is more or less objectionable.

The objects of the present invention are to provide an improved process or method for automatically and continually adding a pure liquid or solution to the treating chamber while removing a portion of the contaminated solution therefrom; to provide a novel process and apparatus for carrying out the process, in which the treating solution is introduced into the treating chamber continually and completely removed therefrom intermittently whereby the articles subjected to treatment are alternately relieved and supplied with the treatment whereby an alternate flooding or soaking and then a draining or suction action is developed on the treated articles; to subject the articles to a treating fluid confined within a closed circuit or course in which the liquid is given a cycle of operation involving the introduction of the liquid into the treating chamber for treating the articles therein, then substantially exhausting the chamber of such liquid, and finally rejuvenating the solution or purifying the same for re-introduction

into the chamber during a succeeding cycle of operation.

The invention also resides in the process of continually adding a cleansed solvent or solution to a treating chamber, effecting relative agitation between the solution and the materials treated within the chamber, and intermittently removing the solution from the latter; in the novel method of purifying the solution after removal from the treating chamber and prior to reintroduction therein; and in an improved apparatus for carrying into practice the novel process, as will be set forth more clearly in the following detailed description.

In the practice of my improved method or process of treating articles with liquids I have shown on the attached sheet of drawings a simplified and more or less diagrammatic view of an apparatus,

Fig. 1 depicting the apparatus for treating articles or material confined within the treating chamber, and

Fig. 2 showing in fragment an apparatus for carrying out my process on articles which are fed continually or intermittently into the treating chamber.

Referring particularly to Fig. 1, I have shown at 1 the treating chamber which is connected in fluid circuit with a tank or reservoir 2 by a feed pipe or conduit 3 and a return pipe or conduit 4, the feed pipe being preferably divided into branches 3' and 3" for purposes hereinafter set forth. This arrangement provides a closed fluid circuit including the reservoir 2, the pipe 3, the treating chamber 1 and the return pipe 4.

Within the treating chamber is preferably provided a support for articles, the support in Fig. 1 being indicated as a basket or cage 5 in which the articles are contained during treatment. During the process of treatment the solution or solvent is retained in the treating chamber 1 until a certain depth is reached following which the liquid is drained

back into the reservoir 2. In this particular case the operative depth to which the liquid is permitted to reach in the treating chamber is sufficient to substantially cover or submerge the cage 5 so as to flood and thoroughly soak the articles therein, following which the liquid is drained from the treating chamber back into the reservoir. This controlled draining or exhaustion of the liquid from the treating chamber is preferably automatic and the preferred automatic control of this liquid exhaustion is in the form of a siphon 6 provided in the return pipe 4, the height of the siphon being coextensive with the highest liquid level attainable in the treating chamber. Consequently, with the siphonic control the collected liquid in the treating chamber will automatically drain from the latter upon reaching a level in said chamber in the plane of the bend in the siphon 6, and after the siphon has initiated the draining flow its operation will effect practically a complete drainage of the liquid from said chamber, whereupon the siphon 25 will be broken and the continually inflowing liquid will again be trapped and collected until the siphon-actuating level is again reached. Thus, the articles confined within the basket 5 are alternately submerged and drained so that the effect on the articles will be to thoroughly wet or soak the same and then drain, in the nature of a suction or wringing action which is further enhanced by the weight of the upper articles settling 35 on the lower articles in the basket.

There is also provided a certain agitation of the liquid so as to bring the liquid or solution into forceful contact with the articles. To accomplish this the basket is preferably moved within the treating chamber so as to agitate the liquid and cause it to move through the articles within the basket. In carrying this thought into practice, the basket is mounted on a vertical shaft 7 which is journaled in a bearing 8 and adapted to be driven by a source of power (not shown) whereby the basket will be rotated or oscillated to stir the articles contained therein and cause the fluid to penetrate and permeate 50 the articles for a more thorough treatment.

The articles may be introduced into the basket through a closure 9 which is movable to a position opposite the closure 10 of the treating chamber. For the purposes of directing the inflowing liquid to a point central of the basket, the latter is provided with a funnel-like hopper or receiver 11 immediately beneath the discharge end of the feed pipe 3, such hopper directing the fluid to the center of the basket from which it is thrown outwardly through centrifugal force during rotation of the chamber. Therefore, the articles within the basket are initially subjected to a radial flow of the liquid through 60 the basket, followed by a more or less flota-

tion and agitation of the articles in the liquid after it reaches a predetermined level therein, and then a final draining or wringing action when the liquid is siphoned off.

As above stated the liquid is fed into the 70 treating chamber by means of pipe 3 in a continuous stream or substantially so. In order to effect this flow or current of the liquid through the pipe 3 suitable flow-inducing means are provided. In branch 3" I 75 have provided mechanical means indicated by a force feed pump 12, the inlet of which communicates with the reservoir 2 at a point below the mean level of the liquid contained therein. A suitable filter or strainer 13 may 80 be provided in this branch so as to remove the major portion, if not all, of the suspended impurities in the liquid drawn from the reservoir by the pump to be discharged into the treating chamber. This closed fluid circuit 85 through the pump is admirably adapted for the treating of certain articles or material, but where it is desired to have the liquid in its purest state when fed to the treating chamber the closed circuit is through branch 90 3', shunting entirely the branch 3".

The means for inducing the flow through branch 3' comprises a vaporizer and a condenser, the former heating the liquid in the reservoir by applying heat thereto. This 95 heat may be applied electrically or otherwise although in the preferred showing I have equipped the reservoir with a steam jacket 14 having a steam inlet pipe 15 and an out-flow pipe 17, suitable valves 16 being provided in these pipes to regulate the heating. The vapors, arising from the liquid in the reservoir, are conducted upwardly through the branch 3', and before being discharged into the treating chamber are condensed into 100 liquid form by means of a condenser such as that indicated at 18, so that the liquids of condensation will discharge in a steady stream from the pipe 3 into the treating chamber. In order to insure a practically pure liquid 110 being fed into the treating chamber the branch 3' may be provided with a strainer or filter of charcoal or other suitable formation to be inserted in the branch 3' at any desired point, either preceding the condenser 115 18 as shown at 19, or following the same as indicated at 19' for acting to remove any coloring matter in the liquid. Sodium carbonate and caustic soda are added to the reservoir 2 to saponify the grease and fatty acids and 120 also neutralize the sweat and acids. The discharge end of the siphon 6 is preferably carried down to a point in proximity to the bottom of the reservoir and is confronted with a baffle 20 to thereby avoid an unusual disturbance of any sediment which may collect at the bottom of the reservoir. The supply of liquid may be replenished from time to time through the filling pipe 21, and the temperature of the liquid within the reservoir may 125 130

be readily ascertained by means of a thermometer such as that indicated at 22.

The treating solution or liquid may be of that character or composition best suited for the articles to be treated. For example, if fabrics or articles of wearing apparel are to be cleaned, the solution may well be gasoline. Considering for the moment that a batch of dark clothes are to be cleaned, the same having been inserted into the basket 5—the pump 12 is put in operation to lift the gasoline from the reservoir 2 for discharge through the pipe 3 into the reservoir 11 and from thence into the clothes within said basket. The basket is oscillated or rotated continuously and as the gasoline collects in the treating chamber 1 the clothes will be agitated and swished about in the collected gasoline until the level of gasoline reaches the maximum height as determined by the siphon 6 whereupon the siphon will commence its operation and exhaust the treating chamber of the liquid whereupon the siphon will automatically cease to operate. Obviously the drainage capacity exceeds the volume of inflow where the inflow is continuous. As the gasoline drains from the clothes in the basket 5 it will draw off the dirt, grease and other foreign matter from the clothes. Furthermore, with the centrifugal force of the rotating basket the residual liquid will be forcefully ejected so as to leave the clothes semi-dried or in a slightly dampened condition. As soon as the siphon is broken by the depletion of the supply of gasoline in the treating chamber the continually inflowing gasoline will again begin to collect within said chamber and start another cycle of operation. By means of a window or sight opening 23 the relative purity of the returned gasoline may be readily ascertained for determining the approximate extent to which the clothes have been cleaned.

After stopping the cycles of operation and shutting off the pump 12 the residual solvent may be removed from the clothes, if desired. This may readily be accomplished by heating the treating chamber in a suitable manner, such as by jacketing the chamber, as indicated at 24, and admitting steam thereto through pipe 25 and exhausting the steam therefrom by pipe 26. The vapors arising from the clothes will then pass through the pipe 3 and downwardly through the filter 19 to be condensed therebelow by means of a condenser 27 before passing into the reservoir 2. Obviously the condenser 18 will be inactive during this drying operation, and during the cleaning operation the condenser 27 will likewise be inoperative. During the cleaning cycle of operation any vapors which pass over into and collect in the treating chamber may be condensed by means of a condenser 28 applied to the treating chamber or a dome 29 communicating therewith. Any condensed gasoline va-

pors collecting in this dome will obviously drop into the receiver 11 and thence pass on into the clothes. Previous to the drying operation any collected gasoline in the treating chamber may be removed, which removal is accomplished by shunting the siphon 6 and draining the gasoline direct into the reservoir through a valved drain-branch 30.

If it is desired to clean white or light color in the basket 5 and, in lieu of utilizing the pump for creating a flow, the gasoline within the reservoir is vaporized by the application of heat thereto and the vapors passed upwardly through the branch 3' and its embodied filter 19, converted back into pure gasoline by the condenser 18 and delivered in liquid form to the treating chamber by pipe 3. The same operation of agitating the apparel in the liquid as it collects in the treating chamber follows as in the former instance. As soon as the collected gasoline in the treating chamber reaches the siphon-initiating level the siphon 6 will begin to drain the gasoline back into the reservoir and after the draining is completed and the siphon broken the condensed liquid continuously being fed into the treating chamber by means of pipe 3 will again be collected to begin another cycle. In these cycles of operation practically pure gasoline is delivered to the treating chamber, and by observing the condition of the gasoline when returned to the reservoir, through the window 23, the cleanliness of the apparel in the basket may readily be determined. These articles of apparel may then be dried as in the former instance.

From the foregoing it will be noted that the cleaning or treating solution is fed continuously to the treating chamber, is removed intermittently therefrom so that there will be an interval during which the liquid collects in the treating chamber, and is rejuvenated or purified either mechanically or through the vaporization and condensation thereof and is then again fed into the treating chamber. We thus have a closed circuit in which the liquid is delivered to the articles being treated in a pure or relatively pure state and is intermittently removed from the articles so that the liquid, which is contaminated with the grease and foreign matter on the clothes, is removed and a fresh supply provided so that each successive washing or treatment is begun in a relatively pure liquid and each successive removal of the collected liquid is less contaminated than the preceding removals as the articles become cleaner. Further, by the intermittent removal of the liquid from the treated articles the draining action tends to loosen or remove foreign matter from the articles which is not possible where the liquid is maintained at a definite and constant level. By the drying operation the articles may be

- completely dried before removal from the basket. The same treating fluid is used over and over again without any substantial loss of content because of the closed circuit and yet 5 each portion of liquid delivered to the treating chamber is relatively pure. The collected sediment in the reservoir 2 may be removed at stated intervals by means of a draw-off passage 31.
- 10 The intermittent drainage of the washing solution from the treating chamber is preferably performed automatically, and in the disclosure in Fig. 1 the siphon 6 comprises this automatic regulator or control but obviously a float-controlled contrivance such as is 15 depicted in Fig. 2 may be utilized when desired. In this more or less diagrammatic view the treating chamber 1' is provided with an endless article-feed or support in the form of 20 a belt 5'. This belt is preferably guided in above the maximum level of the liquid in said chamber 1' and then directed downwardly to submerge the articles carried thereby in the collected liquid. An agitator 7' may be provided in the chamber for agitating the endless 25 conveyor with its supported articles or material, if agitation is desired. A valve 4' is inserted in the drain or exhaust pipe 4" for exhausting the liquid from the chamber 1', 30 this valve being controlled by a float 32 connected by a chain 33 to a system of levers 34 which latter is connected to the valve 4' so that when the liquid is exhausted from the chamber 1' and the float drops, its weight will 35 act to close the valve and when the collecting liquid lifts the float the latter will open the valve.

The form of the invention disclosed in Fig. 2 is especially adapted for the treatment of 40 paper pulp or other material or articles which could be fed continuously or intermittently to the chamber 1' the treating solution in such cases varying with the circumstances, the terms "material" and "article" being used interchangeably. Water or other solvents may 45 be used depending upon the material to be treated. The liquid may be cleansed before it reaches the chamber 2' or subsequently thereto, such as by means of a strainer or filter indicated at 13'.

In the case of dry cleaning wearing apparel, for instance, the flow of gasoline or other liquid from the reservoir to the treating chamber may be through the pump at 50 first, which flow is mechanically cleansed by reason of the filter or strainer 13. This flow may be continuous throughout the entire 55 cleansing operation, but if it is desired to have the last or final soaking and cleansing actions in an absolutely pure liquid, the pump could be cut off and heat applied to the reservoir to distill the gasoline over into the treating chamber through branch 3' so that a practically pure liquid will be fed into the treating 60 chamber.

The reservoir has been shown below the treating chamber but obviously this might be mounted on the same level or even thereabove, a suitable and intermittently controlled pump being located in the return pipe 4, and if the reservoir is located above the treating chamber the pump 12 in branch feed pipe 3" may be dispensed with because a flow in that instance would be by gravity. 70

After a considerable quantity of sediment, 75 grease, soap, etc., accumulates at the bottom of reservoir 2 it may be desirous to remove the same and purify the gasoline or other liquid. This may be accomplished by closing a valve 6' to prevent operation of the siphon, 80 then heating the reservoir 2 to distill the gasoline over into the treating chamber 1, and finally after all or substantially all of the gasoline has been distilled, the sediment and other residue in said reservoir may be removed through the drain pipe 31. After the reservoir has been cleaned and the drain pipe closed, the valve 30 may be opened to drain the purified gasoline or liquid back into the reservoir, attention being given to the closing 85 of the valve 30 after the quantity of gasoline has been returned to the reservoir, and the opening of the valve 6'.

Obviously after a batch of articles has been 90 washed or cleansed in the basket 5 and the drying operation remains to be carried out, a considerable quantity of residual gasoline or liquid may be removed from the articles in the basket through centrifugal action, following 95 which the heat applied to the treating chamber will effect a complete drying of the articles. 100

The mechanical filtering or purification of the liquid by means of the screen 13 is of course assisted by the chemicals in the reservoir when such chemicals have been added. In certain treating operations it may not be 105 advantageous to add such chemicals but where they are added and the saponification takes place the soapy formation will collect at the bottom of the reservoir leaving the lighter liquid which is drawn off by the pump in a 110 relatively pure state.

I claim as my invention:

1. The process of treating material consisting in continually supplying a pure solution to the articles being treated, agitating the material in said solution, collecting the solution to a material-submerging level, and then quickly removing the collected solution from the material. 115

2. The process of treating material or articles consisting in continually supplying a solvent solution for dirt and grease to the material to be treated, intermittently collecting the solution so as to intermittently submerge the material in the collected solution, intermittently removing the collected solution from the material, and then returning 120 125 130

the removed solution to the material for another cycle of treatment.

3. The process of treating material or articles consisting in continually supplying a solvent solution for dirt and grease to the material to be treated, collecting the solution so as to submerge the material in the collected solution, intermittently removing the collected solution from the material, and then purifying the removed solution and returning it to the material for another cycle of treatment.

4. A method of treating articles consisting in providing an article-treating chamber, feeding a solvent to the chamber, removing the solvent from the chamber, continuously agitating the articles in the chamber during the feeding of the solvent as well as during the removal of the solvent from the chamber, purifying the removed solvent and returning it to the chamber for another cycle of treatment, all within a closed circuit.

5. The method of treating or cleansing articles consisting in providing a treating chamber in closed circuit with a solvent solution reservoir, feeding the solution from the reservoir into the treating chamber continuously, and removing the solution from the treating chamber intermittently and returning it to the reservoir.

6. The method of treating or cleansing articles consisting in providing a treating chamber in closed circuit with a solvent solution reservoir, feeding the solution from the reservoir into the treating chamber continuously, removing the solution from the treating chamber and returning it to the reservoir intermittently, and purifying and re-feeding the returned solution to the treating chamber.

40 7. The method of treating or cleansing articles consisting in providing a treating chamber in closed circuit with a solvent solution reservoir, feeding the solution from the reservoir into the treating chamber continuously, removing the solution from the treating chamber and returning it to the reservoir intermittently, interrupting the feed of the solution to the chamber and applying heat to the latter for removing the residual solvent from the articles being treated, and returning the removed residual solvent in solution to the reservoir.

55 8. The method of treating or cleansing articles consisting in providing a treating chamber in closed circuit with a solvent solution reservoir, feeding the solution from the reservoir into the treating chamber continuously, removing the solution from the treating chamber and returning it to the reservoir intermittently, and finally interrupting the feed of the solution to the chamber removing the residual solvent from the articles being treated and returning it to the reservoir.

65 9. Article-treating apparatus comprising

a treating chamber, a reservoir, a feed pipe leading from the latter to the former, a return pipe leading from the chamber to the reservoir, said chamber and reservoir being in a closed circuit, means for introducing a flow of liquid from the reservoir to the chamber, means in said return pipe operable intermittently, and subsequent to a predetermined level of liquid being reached in said chamber, for draining the liquid therefrom, and means for agitating the articles and the liquid in the treating chamber prior to and during the operation of said intermittent means.

10. A method of treating articles consisting in providing a closed circuit between a treating chamber and a liquid containing reservoir, creating a flow of liquid from the latter to the treating chamber, intermittently removing the liquid from the treating chamber back to the reservoir, and agitating the articles in the treating chamber in contact with the liquid therein.

11. The process of treating articles consisting in flowing a mechanically cleansed liquid into a treating chamber for contact with articles therein, removing the liquid from the treating chamber at intervals back to a supply reservoir from which the liquid may be again mechanically cleansed and flowed again to the treating chamber, all in a closed circuit, and after the cleansing process has developed to a predetermined point then to interrupt the mechanically cleansed flow of liquid and substitute a relatively purer flow of liquid.

12. The process of treating articles consisting in flowing a mechanically cleansed liquid into a treating chamber for contact with articles therein, returning the liquid from the treating chamber at intervals back to a supply reservoir from which the liquid may be again mechanically cleansed and flowed again to the treating chamber, interrupting the mechanically cleansed flow of liquid, and then distilling the liquid in the reservoir and condensing its vapors over into the chamber for creating a flow of relatively pure cleansing liquid thereto.

13. Apparatus for treating articles comprising a treating chamber, a reservoir, a cleansing liquid feed pipe from the reservoir to the treating chamber, a drain pipe from the chamber to the reservoir, a second feed pipe from the reservoir for discharging into the chamber, a condenser for condensing the vapors arising from the reservoir through said second feed pipe whereby a relatively purified flow of liquid may be delivered to the treating chamber when the flow through the first feed pipe is interrupted, and means for vaporizing the liquid in the reservoir.

14. Apparatus for treating articles comprising a treating chamber, a supply reservoir, a feed pipe from the reservoir to the

treating chamber, a drain pipe from the chamber back to the reservoir, a second feed pipe from the reservoir for discharging into the chamber, means for condensing the vapors arising from the reservoir through said second feed pipe for flowing into the chamber whereby a relatively purified flow of liquid may be delivered to the treating chamber when the flow through the first feed pipe is interrupted, means for vaporizing the liquid in the reservoir, and means for condensing any vapors which may pass into the treating chamber.

JOSEPH F. BOINEY.

treating chamber, a drain pipe from the chamber back to the reservoir, a second feed pipe from the reservoir for discharging into the chamber, means for condensing the vapors arising from the reservoir through said second feed pipe for flowing into the chamber whereby a relatively purified flow of liquid may be delivered to the treating chamber when the flow through the first feed pipe is interrupted, means for vaporizing the liquid in the reservoir, and means for condensing any vapors which may pass into the treating chamber.
